GLOVE

Application filed March 11, 1930. Serial No. 434,936.

The invention is for a glove and has special reference to gloves for lineman's or other workmen's use.

Gloves as presently provided for workmen's use, do not provide sufficient flexibility at intersection of fingers and palm as also at intersection of palm and wrist, and it is also customary to have an outseam or overlap at the intersection of palm and gauntlet.

10 This overlap or outseam usually wears away quickly, resulting in premature discard of the glove. The joint between palm and gauntlet is also formed with stiffening material tacked into the seam resulting in a sharp

15 creasing joint which proves uncomfortable. The joint between fingers and palm is also customarily provided with seams, providing a bulky, stiff and uncomfortable bend when the fingers are retracted. The usual method 20 of forming the thumb does not provide a form fitting thumb, thereby usually requiring separate means applied about the wrist to retain the glove on the hand.

It is for the purpose of doing away with 25 these objectionable features that this invention is evolved.

The main object of the invention is to provide a workman's glove with double palm and flexible palm-finger joint.

30 Another object of the invention is to provide a glove as outlined having a form fitting thumb;

A further object of the invention is to avoid 35 seams or bulges at intersection of palm and gauntlet and terminate the gauntlet stiffening material at a point backward of the wrist joint so as to provide a flexible bend section at the wrist.

A still further object of the invention is to 40 provide a double palm, gauntlet glove which will be self retaining on the hand and provide a full measure of comfort and convenience at the wrist joint and at the palm-finger joints.

Other objects and advantages of the invention 45 will be readily apparent from the drawings and the description as set forth.

Referring to the accompanying drawings

Fig. 1 is a plan view of the invention;

Fig. 2 is a perspective view indicating the

50 lap between the middle and third fingers;

Fig. 3 is an inside view of the palmside section of the gauntlet;

Fig. 4 is a section taken on line 4—4 of Fig. 3;

Fig. 5 is a plan view of the palm section; 55

Fig. 6 is a plan view of the thumb section.

Similar reference characters are used to designate similar parts throughout the several views.

The invention consists of the ordinary four finger and thumb gauntlet glove with double palm, but provided with a form fitting thumb, the palm section overlapping the gauntlet, and the palm-finger seam being disposed away from the natural bend point of the fingers, and having a flap carried beyond the palm and between the middle and third fingers, and terminating the stiffening material in the gauntlet on the palm side at a point back of the natural wrist bend. 70

The glove is formed with the usual back and palm with the usual patterns and stitching, and the fingers have an additional thickness of material 11 on the palm side and provided with the welts 10. The parts so far 75 enumerated are not a part of the invention, which comprises the palm, Fig. 5, thumb, Fig. 6, and inside half of gauntlet, Figs. 3 and 4.

The thumb is made to a special pattern, 80 which, when sewed into the glove provides a form fit from the thumb joint to the wrist.

The palm is made to a special pattern indicated in Fig. 5, the palm side of the index and little fingers being formed from the extensions 12 and 13, the lap 14 extending around the side of the index finger and providing reinforcement against wear at this point. The extension 15 extends back of the thumb toward the wrist, the edge 16 being 85 sewed to the edge 17 of the thumb and the edge 18 overlapping the curved portion 19 of the thumb, the inner face of the thumb being attached at 20. The lap 21 is tucked under the edge of the gauntlet, and together 90 sewed over the edge 22 of the thumb. The flap 23 extends beyond the wrist line indicated at 24, forming a continuous surface extended onto the gauntlet. The flap 25 is 95 tucked under the gauntlet which is received 100

in the slit 26. Flap 27 is partly cut from the fingers 12 and 13, the sides 28 and 29 folding inwardly about the sides of the index and little fingers, and the flap 30 being drawn between the middle and third fingers and tacked into the rear seam at the end 31. The transverse seams 32 are spaced from the palm-finger joint, providing flaps 33 and 34, thus preventing the gathering of the material at the joint when the fingers are bent inward, the seam being placed on a line connecting the ends of the slits at 35, and functioning to attach the upper portion of the outer palm to the inner palm. The wrist flap 23 is sewed to the gauntlet at 24 and 36, obviating the usual connecting seam or tuck at 24, and providing a smooth unbroken surface across the wrist portion.

The gauntlet is formed of the stiffening material 37 usually oak tanned leather with an insert 38 of flexible leather and backing 39 of flexible leather or other material, the portion 38 within the curved line 40 providing a flexible wrist connection.

Having described an operable method of constructing the glove, it will be understood that minor variations in design and arrangement which are consistent with the appended claims may be resorted to without detracting from the spirit or scope of the invention or sacrificing any of the advantages thereof.

We are aware that gauntlet gloves have been made with a double palm, therefore we do not claim such a combination broadly, but we do claim:

1. A double palm gauntlet glove provided with a palm with integral index and little finger, an integral flap between said index and little fingers, a flap projecting from and integral with said integral flap, said flap being tacked to the back finger-seam, a thumb adapted to fit the contour of the hand from the thumb joint to the wrist, a gauntlet, the palm side of which has stiffening material with a cut away portion adjacent the wrist and replaced by a flexible material, said palm continuing across the wrist seam and extending beyond said cut away portion providing a continuous unbroken surface across said wrist.

2. A double palm gauntlet glove provided with a palm with integral index and little finger, an integral flap between said index and little fingers, a flap projecting from and integral with said integral flap, the end of said flap being tacked to the back finger-seam, a thumb adapted to fit the contour of the hand from the thumb joint to the wrist, a gauntlet the palm side of which is provided with a stiffening material with a cut away portion adjacent the wrist, said cut away portion being replaced by a section of flexible material attached to said stiffening material, said palm continuing across said wrist and said cut away portion forming a wrist bib

and continuing beyond providing a continuous unbroken surface across said wrist, a flap on said palm adjacent the thumb adapted to form an under tuck about the edge of said gauntlet adjacent the thumb, and a flap at the opposite side of said wrist bib adapted to be tucked directly under said gauntlet.

In testimony whereof we have affixed our signatures.

LAURI A. WICKMAN. 75
